UNITED STATES PATENT OFFICE

2,410,961

ELECTRICAL CONNECTOR

Charles Edgar Carson, Sharon, Mass.

Application March 24, 1945, Serial No. 584,615

2 Claims. (Cl. 287—78)

1

This invention relates to connectors for electric wires and cables, and relates more particularly to connectors for stranded wires and cables.

In connecting stranded, electric cables such as those used in wiring systems on automobiles, solderless connectors known as line connectors are used. Those in most common use consist of metal sheets which are wrapped around and crimped upon the bare wires in the ends of the cables, and of a metal sleeve into which the ends of the cables with the sheets therearound, are forced. Due to the several indirect contacts, the voltage through such connectors is relatively high, and considerable time and care are required for making the connections.

This invention provides a line connector which not only is less expensive to manufacture than prior connectors, but is easier to apply and has a lower voltage drop. A feature of the invention is that there are no indirect contacts. Another feature of the invention is that most of the material used preferably is non-metallic and may be of any inexpensive plastic.

Objects of the invention are to reduce the manufacturing and installation costs of line connectors for electric wires and cables, and to reduce the voltage drops through such connectors.

The invention will now be described with reference to the drawing, of which:

Fig. 1 is a side elevation illustrating two electric cables interconnected by a line connector embodying this invention;

Fig. 2 is an exploded view of the assembly of Fig. 1 with parts in section;

Fig. 3 is an enlarged section similar to Fig. 5 but taken before the connector is tightened upon the wires;

Fig. 4 is a sectional view along the lines 4—4 of Fig. 3;

Fig. 5 is a sectional view along the lines 5—5 of Fig. 1;

Fig. 6 is a sectional view along the lines 6—6 of Fig. 5, and

Fig. 7 is an end view in reduced scale of the retaining ring used.

The connector illustrated includes the sleeve 10 which preferably is of plastic material, and which has the cylindrical openings 11 in the opposite ends thereof for receiving the insulated ends of the cables 12 to be connected, and which has the central, cylindrical opening 13 for receiving the bare ends 14 of the cables.

At about the center of the sleeve 10, there is a rectangular slot 15 arranged to receive the plunger 16 which preferably is of metal. The

2

cam member 17 which preferably is of plastic material, has an internal spiral shaped, cam opening 18 which is provided for forcing the plunger 16 against the wires as will be described. The opening 18 has a rounded enlargement at 21 which is shaped to conform with the curved top of the plunger 16 and which receives the said curved top when the connector is fully tightened as illustrated by Fig. 6.

10 The sleeve 10 and the cam member 17 are externally knurled except that the sleeve has a smooth portion at 22, and the cam member has a smooth portion at 23, as illustrated by Fig. 1, for indicating the relative positions of the plunger 16 in the slot 18 as will be described. The sleeve 10 has a raised shoulder 30 of increased diameter having adjacent, and to one side of, the slot 15, the transversely extending wall 31, and the cam member 17 has a transverse wall 32 in contact 20 with the wall 31, the wall 31 serving as a retaining wall during rotation of the cam member.

15 The ring 19 which preferably is of metal, is provided for maintaining the cam member 17 assembled in its proper position upon the sleeve 10 as illustrated by Figs. 3 and 5, and preferably has the inwardly extending, sharp teeth 20 which cut into the surface of the sleeve 10 when the ring is forced thereon, whereby the ring remains tightly 25 in the connector assembled position as illustrated by Figs. 3 and 5.

20 The connector is assembled by placing the cam member 17 on the sleeve 10 and by then placing the locking ring 19 against the cam member as illustrated by Figs. 3 and 5. The connector can 25 be assembled at the time the cables are to be connected together or at any time prior thereto.

25 When cables are to be connected, the cam member 17 is rotated to the positions shown by Figs. 3 and 4 whereby the plunger 16 may be 40 placed in the widest portion of the opening 18 so it cannot obstruct the passage of wires through the opening 13. At this time the smooth portions 22 on the sleeve 10 and 23 on the cam member 17 will be in alignment as illustrated by Fig. 1. The

45 connector is then turned until the smooth portions 22 and 23 are uppermost at which time the plunger 16 will fall by gravity into the widest portion of the opening 18. The cable ends are then inserted so that their strands intermesh as 50 illustrated by Figs. 3 and 4. The cam member 17 is then rotated counter-clockwise with reference to Figs. 3 and 4 through an angle of 270 degrees. During this rotation the inner end of the plunger 16 will be forced against the wire strands as a result 55 of the pressure of the wall of the cam open-

ing 18 against the top of the plunger, and the wire strands will be compressed between the inner end of the plunger and the bottom of the slot 15 as illustrated by Figs. 5 and 6. At the end of the travel of the cam member, the curved outer end of the plunger will snap into the curved depression 21 in the wall of the cam opening 18 of the cam member, thereby locking the cam member in cable connecting position. At this time, the smooth portion 22 on the sleeve 10 will be 90 degrees out of alignment with the smooth portion 23 on the cam member 17.

Since through the use of the connector of this invention there is direct wire to wire contact under considerable pressure, the electrical resistance of the connection is a minimum.

Another advantage of this connector is that the bare strands of the cable ends are isolated from the exterior of the connector by the insulation thereof so that no grounds or shorts can occur through the exterior of the connector touching the frame of a car or other metal.

While one embodiment of the invention has been described for the purpose of illustration, it should be understood that the invention is not limited to the construction illustrated, as modifications thereof may be suggested by those skilled in the art without departure from the essence of the invention.

Having described one embodiment of the invention, what is claimed is:

1. A connector comprising a sleeve having a longitudinally extending opening for the reception of cable ends to be interconnected and having an aperture extending from the exterior of said sleeve transversely into said opening, said sleeve having a raised shoulder portion with a transversely extending wall adjacent said aperture, a cam member having a wall in contact with said wall and having an internal cam surface around said aperture, a plunger in said aperture, said plunger having an outer portion in contact with said surface whereby upon rotation of said member around said sleeve, said plunger is forced by said surface inwardly in said aperture for forcing wires in said opening intimately in contact, and a locking member around and in contact with said sleeve and in contact with said cam member for maintaining said cam member in position relative to said aperture.
2. A connector according to claim 1 in which the sleeve is of relatively soft material, and the locking member is of metal with teeth which grip the surface of the sleeve.

CHARLES EDGAR CARSON.
